UNITED STATES PATENT OFFICE.

CHARLES W. MAYER, OF ROCHESTER, NEW YORK.

POWER-LOADING WAGON.

1,111,846.

Specification of Letters Patent. Patented Sept. 29, 1914.

Application filed October 4, 1913. Serial No. 793,345.

To all whom it may concern:

Be it known that I, CHARLES W. MAYER, a citizen of the United States, and resident of Rochester, county of Monroe, State of New York, have invented an Improvement in Power-Loading Wagons, of which the following description, in connection with the accompanying drawings, is a specification, like characters on the drawings representing

like parts.

The present invention relates to vehicle or wagon bodies equipped with power operated means for filling the same, and is equally well adapted for either horse drawn or motor driven vehicles. While having other and more general fields of usefulness the invention is well adapted for use in the ash, garbage and refuse collections of cities, being adapted to receive and handle both heavy and bulky loose material rapidly and easily with a minimum of manual labor and attention.

One of the objects of the invention is to provide such vehicles with simple, positive and reliable means for elevating a suitable receiving bucket from a position on the ground to a position over the vehicle-body and for automatically inverting it to dump its contents, on reaching the proper position.

A further object is to so construct the automatic dumping mechanism that the bucket may be inverted at different points over the vehicle-body to distribute the load.

Referring to the drawings: Figure 1 is a side elevation of a vehicle body equipped with a preferred form of my improved power loading mechanism; Fig. 2 is a detail elevation showing one form of bucket lifting arm with operating connections and counterbalance device carried thereby; Fig. 3 is a fragmentary detail of a part of the bucket dumping means.

The wagon body is indicated at 10 equipped with usual or suitable front and rear rolling stock 11 and 12 respectively. This body is shown as an unusually high one to illustrate the possibilities of my invention for easily filling such a body and thus handling large loads. The tops of the body sides are preferably formed with arcuate upward extensions intermediate of the length thereof as indicated at 13. These raised convex arcuate portions serve a double purpose of furnishing retaining walls to

hold the natural piling up of the refuse near the middle of the body, and one of these raised portions also serving as a mounting for pins adapted to effect the dumping of the receiving bucket as hereinafter explained. The receiving bucket into which the garbage or other material to be handled is deposited, is indicated at 14 of tapering form so as to be convenient for filling and likewise more easily dumped when inverted. 60 This bucket has journals or trunnions 15 at its sides somewhat above its center of gravity pivotally engaged with the ends of arms 16 at the sides of the body, these arms being mounted on journal bearings 17 at a point 70 well down on the body. The arms 16 are extended beyond their pivotal support 17 to form arcuate extensions equipped with gear segments 18 engageable by pinions 19 on a shaft 20 journaled at the base of the body 75 and extending thereacross. This shaft 20 has fixed thereto at one side a hand crank 21 whereby the mechanism may be manually operated when desired. I preferably provide also motor operated means for lifting 80 the bucket and to this end I show a shaft 22 mounted at the side of the body having gear connection 23 with the shaft 20, this shaft 22 being driven by suitable gear connections 24 from a motor 25 shown as mounted beneath 85 the driver's seat 26.

The carrying arms 16 are of such length as to permit the bucket to rest on the ground at the rear of the vehicle-body, to be conveniently filled and to carry the filled bucket 90 up over the body where it is automatically tipped or inverted for dumping it.

As a means for tipping over and dumping the bucket when it comes to position over the body, I fix at one side thereof a gear or 95 pin wheel 27 concentric with the journal axis 15. The teeth of this wheel are engageable by a series of pins mounted near the top edge of one of the raised arcuate side portions 13 of the body and it may now be 100 noted that these raised side body portions are formed on an arc concentric with the swinging axis 17 of the bucket, said pins being likewise concentrically mounted so that they will engage and operate the teeth 165 of wheel 27. These pins thus practically form a gear rack. I preferably mount said pins so that a set 28 of them which the wheel 27 would first engage on coming over the top rear portion of the body, may be 110

2
swung out of operative position at will. To this end this set of pins 28 instead of being carried by the side of the body itself are carried by a plate 29 swingingly mounted at 30 with an outwardly projecting operating handle 31 and a spring pressed engaging detent 32 adapted to engage one of two recesses in the plate to hold the pins either in operative or inoperative position at will. These pins when in operative position project through holes in the side of the body to a point where they will engage the teeth of wheel 27 to turn the bucket over for dumping, but when the plate 29 is swung out, said pins are withdrawn so that they do not engage the teeth of wheel 27 but permit the bucket to pass this point without being turned over for dumping. In this case the teeth of wheel 27 are engaged by a succeeding set of pins 33 mounted on the side of the body and projecting inward therefrom so that the bucket will be dumped as shown substantially over the center of the body. It is to be understood that this showing is merely illustrative and that any desired number of sets of pins or any equivalent means adjustable as may be found most advantageous for dumping into different parts of the body may be employed within the spirit of my invention.

In Fig. 2 I show a form of the invention wherein the lifting arms 16' instead of having an external gear segment 18 are equipped with an internal gear segment 18' engaged by an operating pinion 19' which may be mounted on a shaft 20 with operating connections the same as in the first described form.

If desired, suitable means may be employed for partly or wholly counterbalancing the weight of the bucket and its contents. For example, as shown in Fig. 2, a counterweight 39 may be applied to one or both of the bucket-carrying arms 16' for this purpose.

It is to be observed that the operating mechanism required for lifting and dumping the bucket is exceedingly simple and of few parts with nothing ever likely to get out of order and that the dumping of the bucket as well as the turning back thereof to receiving position entirely automatic, the dumping being effected with certainty and precision at the desired part of the body. Further the raised arcuate top portions 13 at the sides of the body permit filling of the same with a larger load and at the same time provide a convenient mounting for the dumping pins.

I am aware that the invention can be embodied in various other specific forms as to details of construction without departing from the spirit thereof and I therefore desire the present embodiment to be considered as illustrative and not restrictive to the appended claims to indicate the scope of the

invention. For example, the gear wheel 27 might be constructed in the form of a gear segment, if desired, as only a portion of its toothed periphery is required in practice.

Having described my invention what I claim as new and desire to secure by Letters Patent is:

1. Apparatus of the kind described, comprising a vehicle-body, vertically-swinging arms carried by the body, a receiving-bucket having trunnions journaled directly on said arms, and coöperating means on the bucket and the vehicle-body whereby the bucket is automatically inverted for dumping as it comes to position over the body. 80

2. Apparatus of the kind described, comprising a vehicle-body, vertically-swinging arms carried by the body, means other than the vehicle-wheels and axles for lifting said arms, a receiving-bucket having trunnions journaled directly on said arms, and coöperating means on the bucket and the vehicle-body whereby the bucket is automatically inverted for dumping as it comes to position over the body. 90

3. An apparatus of the kind described, comprising a vehicle-body, vertically-swinging arms pivoted to the body, a receiving bucket journaled on said arms and carrying a gear wheel, the vehicle-body carrying a gear-rack arranged to be engaged by said wheel for automatically inverting the bucket, and means for lifting said arms. 95

4. An apparatus of the kind described, comprising a vehicle-body, vertically-swinging arms pivoted to the body, a receiving bucket journaled on said arms and carrying a gear wheel, the vehicle-body carrying a gear-rack curved concentrically with said arm-pivots and arranged to be engaged by said gear wheel when said arms are elevated, and means for lifting said arms. 100

5. Apparatus of the kind described, comprising a vehicle body, swinging arms mounted on the body, a receiving bucket journaled at the ends of said arms, and means for effecting a turning over of the bucket to dump the same as it comes to a predetermined position over the body, said means consisting of a toothed member rigid with the bucket and a series of pins disposed in an arc at the top of the body, certain of said pins being movable to inoperative position to permit the bucket to pass the same before being dumped. 115

6. Apparatus of the kind described, comprising a vehicle-body, a receiving bucket, and means for inverting the bucket for dumping at a determinate position over the body, said means consisting in teeth rigid with the bucket, and coöperative means on the body for engaging said teeth, including a swinging plate and pins carried thereby to be movable out of operative position, permitting the bucket to pass the same before 120 130

being dumped, and means for raising the bucket to dumping position.

7. Apparatus of the kind described, comprising a vehicle body, swinging arms mounted on the body, a receiving bucket carried by said arms to rest on the ground and be lifted up over the body for dumping at will, coöperative means on the bucket and body for automatically inverting the bucket for dumping as it comes to position over the body, and means for operating said arms to lift

the bucket, said means consisting in gear segments formed rigid with the arms and motor operated gear connections engaging said gear segments.

In testimony whereof, I have signed my name to this specification, in the presence of two subscribing witnesses.

CHARLES W. MAYER.
